(57) **CLAIM**

We claim the ornamental design for the T-spline joiner, as shown and described.

DESCRIPTION

FIG. 1 is a front perspective view of the T-spline joiner embodying our design;

FIG. 2 is a front elevational view of FIG. 1;

FIG. 3 is a side elevational view of FIG. 1, the other side being identical;

FIG. 4 is a top plan view of FIG. 1; and,

FIG. 5 is a bottom view of FIG. 1.
